UNITED STATES PATENT OFFICE.

WARREN McARTHUR, JR., OF PHOENIX, ARIZONA.

AUTOMOBILE RADIATOR CONSTRUCTION.

Application filed July 16, 1924. Serial No. 726,237.

This invention relates in general to automobile radiator construction and more particularly to a construction and arrangement of the parts so that various types of radiator caps may be locked on the necks of the radiator, said construction permitting large devices, such as the well known motometer or other temperature indicating devices to be formed integral with or removably locked on the radiator cap or neck.

At the present time, the conventional radiator construction is to have a core or cooling section separate from and fastened to an outer shell. The core is provided at its top with a neck, permanently fastened thereto, for the purpose of filling the core with a cooling medium. The usual method of fastening the core into the shell is by bolts or other means so that should it become necessary to repair or replace the core, the core can be removed from the shell by removing the cap from the neck and unfastening the bolts so that the shell can be pulled outwardly from the bottom of the core and then raised upwardly until the top of the shell is lifted sufficiently high to clear the top of the neck which extends through an opening in the top of the shell.

In providing a theft-proof radiator neck cap it has been necessary heretofore to incorporate in it some device that will facilitate the removal of the cap from the neck, when it becomes necessary to remove the shell for purposes of repair or replacements of the core. The removal of these theft-proof radiator neck caps is at times an inconvenient, tedious and difficult operation. With the present day type of radiator construction the radiator caps must be removed before the shell can be lifted from the core, because the caps are larger than the opening in the top of the shell and consequently will not pass through such opening.

Objects of the invention are the provision of a radiator constructed so that such theft-proof radiator caps may be securely locked on the neck of the radiator, or formed as an integral part of the neck; the provision of a construction which will permit ornamental or other devices to be formed integral with the neck or cap; the provision of a construction which will permit temperature indicating devices extending above the top of the neck or cap to be securely locked on said neck or formed as an integral part of the neck or

cap; the provision of a construction, in which the neck is detachable from the core and shell to permit removal of the core from the shell for purposes of repair and replacement; the arrangement of the parts in such a construction so that the neck will be locked against removal while the parts are in assembled position, such arrangement permitting the removal of the neck only upon partial detachment of the shell from the core and such other objects and advantages of the invention as may be found to obtain in the structure hereinafter set forth and claimed.

In the accompanying drawings, forming a part of this specification, and showing, for purposes of exemplification, a preferred form and manner in which the invention may be embodied and practiced, but without limiting the claimed invention specifically to such illustrative instance or instances:

Figure 1 is a front elevational view of an automobile radiator embodying my invention.

Fig. 2 is a side elevational view of the same.

Fig. 3 is a top plan view of a radiator neck having a cap and temperature indicating devices formed integral with the neck.

Fig. 4 is a front elevational view, parts being shown in section, of the neck, cap and temperature indicating device.

Fig. 5 is a vertical cross-sectional view taken on the line 5—5 of Fig. 4.

Fig. 6 is a vertical cross section of another form of construction embodying the invention.

Fig. 7 is a partial front elevational view and partial vertical cross-sectional view taken on the line 7—7 of Fig. 6.

Fig. 8 is a partial top plan view and partial horizontal sectional view taken on the line 8—8 of Fig. 7.

Fig. 9 is a side elevational view of said other form of construction.

On the drawings, 10 is the radiator shell having upwardly extending sides 11 and a curved top 12. Brackets 13 having apertures 14 therein are provided at the lower portions of the sides 11 to secure the shell to similar brackets on the core. The top 12 of the shell is provided with an opening 15, shown as circular in Figs. 1 to 5 and as elliptical in Figs. 6 to 9, portions of the material about the circular opening in Figs. 1 to 5 are cut away to provide slots 16 in the shell which receive projections on the neck. The core or cooling

section 17 is formed separate from the shell and is provided with brackets 18 at the lower portions of its sides, said brackets having apertures which register with the apertures 5 in the brackets 13 and through which means may pass to secure the core within the shell. The bottom 19 of the shell is provided with bolts 20 that also serve to keep the shell in proper position on the core. The top 21 of the core is provided with an aperture 22 and extending upwardly from this opening is a collar 23 which is permanently clinched at 24 to the material about the aperture 22 in the top 21. At its upper end the collar is threaded on its outer surface 25 to receive the threaded lower end 26 of the removable radiator neck 27 so that the neck can be removably secured on the core, and in order to prevent possible leakage through the joint between the portions 25 and 26 there is provided, at the lower end 26 of the removable radiator neck a gasket 28. The cylindrical neck, illustrated in Figs. 1 to 5, has projections that fit into the slots 16 when the shell is in normal assembled position, said projections having holes for the reception of the ends of a holding down bail 30. The projections 29 extend from the bottom of the neck to a point 31 short of the top of the neck so that when the bail 30 is withdrawn from the projections 29 and the shell is unfastened at the bottom and swung out, as indicated in dotted lines in Fig. 2, it can be raised over the core until the top of the shell clears the top of the projections, thereby releasing the neck from the shell with sufficient clearance to permit unscrewing of the neck from the collar on the core. A filler opening cap 32 is hinged to the front 33 of the upper end of the neck, said cap having a curved slot 34 providing a cam surface 35 upon which the bail rides to hold the cap tightly down in the top of the neck to close the filler opening. The cap is provided with an inclined outer seating surface 36 which rests on a gasket 37 supported by the seat 38 formed integral with the neck. Referring to Figs. 1 to 5, there is shown a frame 40 extending from the top of the neck, said frame being cast integral with the neck. Secured within the frame 40 is a temperature responsive element 41 that extends into the space beneath the top 42 of the neck. The element 41 is protected at its lower end 43 by a metallic tube 44, that is closed at the bottom by a screw plug 45. The upper portion of the element 41 is protected by a metal protector plate 46 and a glass protector 47. The metal plate 46 is provided with an opening 49 to facilitate the visibility of action of the temperature responsive element 41. Referring to Figs. 6 to 9, there is shown an embodiment of the invention in which the hinged cap is secured to the neck to cover the opening in the front of the top of the neck, and to the rear of this cap is provided

a closure member 50 having a screw threaded opening 51 through which the stem 51' of a removable temperature indicating device extends. A locking nut 52 is threaded on the stem beneath the member 50 and secured within the top surface of the member 50 is a plug or set screw 53 pointed at its top and extending slightly above the top surface of the member 50 so that when the nut 52 is tightened it will draw the flange 54, of the portion of the temperature indicating device that extends above the top of the neck, down on the member 50 so that the temperature indicating device cannot be unscrewed from the top but only from the under side of the neck. In the embodiment illustrated in Figures 6 to 9, the neck is formed elliptical at its lower portion as shown at 55, while its inner lower surfaces are cylindrical as indicated at 56. The elliptical portion 55 terminates at its upper end in an inclined annular portion 57 which is integrally connected with a vertically extending cylindrical portion 58 of the neck. When the radiator illustrated in Figs. 6 to 9 is in assembled position, the elliptical portion 55 of the neck is enclosed in the elliptical opening 59 of the shell and is locked therein by the securing of the shell on the core, and while so locked in position the neck proper can not be unscrewed from the core by reason of the shape of the opening in the shell and the lower portion 55 of the neck. To remove the neck, the shell must be unfastened from the core and raised upwardly thereon until the opening in the shell is above the top 60 of the elliptical portion 55 at which point the neck can be readily rotated and unscrewed from the collar and then lifted out of the shell. After the neck is so removed from the shell the nut 52 can be unscrewed and the temperature indicating device removed.

To assemble the radiator constructed in accordance with Figs. 1 to 5, the ends of the bail are withdrawn from the projections 29 and the neck then inserted through the opening in the top of the shell until the top of the projections 29 are beneath the top of the shell, then the neck is screwed tightly down on the collar. After the neck is screwed on the collar the shell is lowered until the slots fit around the projections 29, then the shell is fastened on the core and the ends of the bail inserted in the projections 29.

To remove the core from the shell, the ends of the bail are withdrawn from the projections and the shell unfastened from the core and raised up until the top of the shell clears the top of the projections. Then the neck is unscrewed from the collar and withdrawn from the shell and the shell lifted off of the core.

From the foregoing it will be noted that a temperature indicating or other type of device can be securely locked on the neck of the

radiator and be removed only by access to the interior of the neck, and that the invention provides an arrangement in which such a device can extend upwardly from the top of 5 the neck and be formed as an integral part of the neck or cap; and the neck or cap can be removed only after the shell and core are detached from each other; that an ornamental cap or other devices can be locked permanently to the neck or formed as an integral part of the cap or neck and yet permit removal of the shell from the core without detaching such devices or the ordinary theft-proof cap from the neck.

15 The invention as hereinabove set forth is embodied in a particular form of construction but may be variously embodied within the scope of the claims hereinafter made.

Those features of the invention exemplified 20 in the foregoing description which relate broadly to the locking of a removable neck in position by the shell when assembled on the core and to the removal of the neck only when the shell is detached or partially removed 25 from the core are made the subject matter of my copending application for Letters Patent of the United States, filed July 16, 1924, Serial No. 726,236.

I claim:

30 1. A radiator construction comprising, in combination: a core; a shell therefor; said shell being removable from said core; a radiator neck having temperature responsive means attached thereto, said neck being removably secured on said core; said shell having an opening therein through which said neck extends, said neck and said shell being fashioned to interlock with each other to prevent removal of said neck from said 40 core when said shell is in normal assembled position on said core.

2. An automobile radiator construction comprising, in combination: a radiator core; a radiator shell removable therefrom; said core having an aperture in its top; an annular collar rigidly clinched to the material about the aperture in said core top; said collar being threaded at its upper end; a radiator neck having a temperature responsive device secured thereon, said neck being threaded at its lower end to removably engage the threaded end of said collar; said neck having an elliptical base portion; a cap for said neck; an annular gasket interposed between said neck 55 and said collar; said shell having an elliptical opening in its top in which the elliptical portion of said neck is arranged when said shell is in assembled position on said core; a portion of the neck above said elliptical portion being of reduced diameter.

3. An automobile radiator construction comprising, in combination: a radiator core; a radiator shell therefor and removable therefrom; said core having an aperture in its 65 top; an annular collar permanently clinched

to the material about the aperture in the core top; said collar having screw threads thereon; a radiator neck having a frame attached thereto and extending upwardly therefrom, said neck being screw threaded to removably 70 engage the screw threaded end of said collar; said neck having an elliptical portion and a portion of smaller diameter than the diameter of the elliptical portion, said shell having an elliptical opening in its top to receive the elliptical portion of said neck.

4. An automobile radiator construction comprising, in combination: a radiator core; a radiator shell therefor and removable therefrom, said core having an opening in its top; a collar permanently secured to the material about said opening; a neck detachably secured to said collar; said neck having an elliptical portion and a circular portion; said shell having an elliptical opening in its top 80 through which the elliptical portion of said neck extends.

5. A radiator construction comprising, in combination: a core; a shell therefor, said shell being detachably secured to said core; a radiator neck removably secured to said core; said shell having an elliptical opening in its top through which said neck extends, said neck, having an elliptical portion and a cylindrical portion, said elliptical portion fitting in said elliptical opening.

6. An automobile radiator construction comprising, in combination: a core; a shell therefor; a neck having a temperature indicating device attached thereto, said neck being removably connected to said core, said shell and said neck having a slot and a projection respectively; said projection fitting in said slot when the shell and neck are in assembled position and preventing removal of the shell and neck while said projection is in said slot.

7. A radiator construction comprising, in combination: a core; a shell; a neck removably connected to said core and extending through said shell; a device extending from the upper part of said neck; means on said neck and shell and cooperating to connect said neck and shell directly with each other to prevent unauthorized disconnection of said parts from each other so long as said shell is assembled on said core.

8. A radiator construction comprising, in combination: a core; a shell therefor; a neck removably connected to said core; a device extending from the top of said neck; and means on said neck and shell and directly cooperating to interlock said neck and shell directly with each other while said neck and shell are assembled on said core, said means comprising a slot and projection.

9. A radiator construction comprising, in combination: a core; a shell; a neck connected to said core and removable therefrom by a rotary movement of said neck; a device ex-

tending from the top of said neck; and means on said neck and shell and directly cooperating so that said neck may be interlocked against said rotary movement directly by 5 said shell.

10. A radiator construction comprising, in combination: a core; a neck thereon and removable therefrom by a rotary movement; a shell through which said neck extends; a device united to said neck, said device extending from the upper portion of said neck; said neck having a non-circular portion and said shell having a non-circular opening in its top in which the non-circular portion of

said neck is arranged while said neck and shell are assembled on said core.

11. A radiator construction comprising, in combination: a core; a neck thereon; a shell through which said neck extends; a device on said neck and removable therefrom only 20 after removal of said neck; and means on said shell directly cooperating with a portion of said neck to interlock said neck and shell directly with each other.

In witness whereof I have hereunto set my 25 hand.

WARREN McARTHUR, JR.
